UNITED STATES PATENT OFFICE.

HENRY JOSEPH WELDON, OF BROOKLYN, NEW YORK.

DESIGN FOR A COLLAR.

SPECIFICATION forming part of Design No. 24,259, dated April 30, 1895.

Application filed February 27, 1895. Serial No. 639,940. Term of patent 14 years.

To all whom it may concern:

Be it known that I, HENRY JOSEPH WELDON, a citizen of the United States, residing at Brooklyn, Kings county, and State of New York, have invented and produced an original Design for Collars, of which the following is a specification.

In the drawing the figure shows a front view of the collar.

The leading feature of the design resides in the turned over points which form the three sides of a rectangle with a V shaped central opening between the points closed at the bottom by the abutting vertical edges of the points.

In the drawing the points form vertical lines at the sides which are parallel to each other

and the lower edges form a horizontal line. A central V shaped opening is formed by the angular lines of the folds but as these angular lines do not extend to the lower edge of the points, short vertical lines are formed which abut, giving the appearance as if the points were integral across the bottom thereof.

I claim—

The design for collars herein shown and described.

In testimony whereof I affix my signature in presence of two witnesses.

HENRY JOSEPH WELDON.

Witnesses:

E. C. CARVER,
W. E. HIGGINS.
